UNITED STATES PATENT OFFICE.

JAMES C. CARTER, OF DECATUR, ILLINOIS.

DESIGN FOR A CASING FOR COIN-ACTUATED WHEELS.

SPECIFICATION forming part of Design No. 27,481, dated August 3, 1897.

Application filed April 29, 1897. Serial No. 634,472. Term of patent 7 years.

To all whom it may concern:

Be it known that I, JAMES C. CARTER, of Decatur, in the county of Macon and State of Illinois, have invented a certain new and useful Design for Casings for Coin-Actuated Wheels, of which the following is a specification.

This design is illustrated in isometrical perspective in the drawing forming part of this specification, and its characteristic features are a horizontal base 1, having a circular opening 3 in its upper surface, and a substantially rectangular plate 4, rising vertically from the

base immediately in the rear of the circular opening thereof.

What I claim as new, and desire to secure by Letters Patent, is—

The design for a casing for coin-actuated wheels, substantially as herein shown and described.

In testimony whereof I sign my name in the presence of two subscribing witnesses.

JAMES C. CARTER.

Attest:

ORVILLE B. GORIN,
L. P. GRAHAM.
